COMBINED ROSE AND COLLAR FOR A DOOR KNOB

Fred J. Russell, 8635 Otis St., South Gate, Calif.

Filed Mar. 31, 1964, Ser. No. 79,261

Term of patent 14 years

(Cl. D50—6)

FIG. 1.

FIG. 3.

FIG. 2.

I claim:

The ornamental design for a combined rose and collar for a door knob, as shown.
